BUNCH BUILDING METHOD AND APPARATUS

Edward J. Berry, Providence, R. I., assignor to Draper Corporation, Hopedale, Mass., a corporation of Massachusetts

Application June 13, 1946, Serial No. 676,445

20 Claims. (Cl. 242—27)

1

This invention relates to filling winders. More particularly the invention is concerned with a method and apparatus for building a "finding" bunch of filling on a bobbin at the end of the bobbin winding operation. Reference is had especially to a bobbin winding operation such as is performed by the Whitin-Schweiter automatic filling bobbin winder.

According to the practice to this time, after a package is made, it is customary for the winder to secure the end of the thread by passing it back along the package in a diagonal manner and then forming a few turns. This provides so-called "back-wind." When the bobbin is inserted in a loom battery, it is necessary for the operator to find the thread forming the back wind, and to clear it so that it may be hand-tied to the battery upon insertion of the bobbin therein and preparatory to transfer of that bobbin to the shuttle and to the shuttle making its first pick across the loom. The operation of finding and clearing the end of thread, as well as the hand-tying step, involves an appreciable delay in renewing bobbins with consequent increase in cost of fabric production.

An object of the invention generally is to deal with this problem in connection with bobbin winders, and to devise means for improving the finding and clearing operation noted. It is further an object of the invention to provide a finding bunch so arranged as to facilitate securing a bobbin and its filling in a loom shuttle battery whether the operation is performed by hand or by automatic mechanism. Other objects will be apparent from the following description of the invention.

With the foregoing considerations in mind, I have devised a method and apparatus for building a separate finding bunch on the end of a bobbin without interfering with the usual filling bobbin winder operations. The bunch, when properly prepared, may be removed from the end of the bobbin very easily and quickly and may serve as a convenient means for extending the thread to secure it to the usual thread holder of a conventional battery, or for retaining the end of a filling thread in an automatic type battery during the first pick of the shuttle across the loom.

The accompanying drawings illustrate a preferred embodiment of the invention, in which

Fig. 1 is a perspective view of a filling bobbin winder equipped with bunch building and sealing mechanism according to the invention;

Fig. 2 is another perspective view of a winder embodying the invention as viewed from the opposite side to that illustrated in Fig. 1;

2

Fig. 3 is a detail plan view of an adhesive applying mechanism;

Fig. 4 is an exploded view illustrating further details of the sealing mechanism;

Fig. 5 is an elevational view of the adhesive applying means of Fig. 3;

Fig. 6 is a detail cross-sectional view of the adhesive applicator valve;

Fig. 7 is a side elevation of a carriage retraction cam and a bunch-building cam;

Fig. 8 is a front elevation of the carriage retraction cam; and

Fig. 9 is a front elevation of the bunch-builder cam.

The general plan of the apparatus includes a bunch-building mechanism operatively connected to the doffing mechanism and thread guide of a Whitin-Schweiter automatic filling bobbin winder. The details and operation of this winder are evident in U. S. Patents 2,268,308; 2,268,309 and 2,268,310, and more than a general mention of its conventional operation to wind a weft package need not be given here. When the package has been nearly made, the last few turns of the spindle are utilized to build, at a point just beyond the main body of the package, a finding bunch. The bunch is rather lightly wound so that the turns of filling, in a body, may be readily pulled off over the end of the spindle. As it is being built, the bunch is contacted by a sealing or adhesive applying mechanism and in this way receives an adhesive material which tends to stick together the turns of filling. An adhesive agent of such character is chosen that a positive force such as a firm tug on the thread is required to unwind the turns of the bunch from each other. The adhesive is so applied as not to adhere the bunch to the bobbin, but to provide for sliding movement between the bobbin and the bunch as a whole.

In this way, undesired unwinding of the bunch is avoided in handling, and yet the bunch may be removed as a solid body without difficulty, at the time of loading the bobbin in a loom shuttle battery.

These features are more readily understood from the following detailed description of the mechanism shown in the drawings. Illustrated therein is the filling bobbin winder. The conventional cycle of operations of this winder will first be considered briefly. A thread 9 (Fig. 1) is taken from the end of a supply package and passed through a tension device of the type commonly used in the art. From here the thread moves through an abrasion resistant guide indicated in the drawings by numeral 10, which func-

tions as a stop motion element, and on through an oscillating thread guide 14.

The thread guide 14 traverses the thread on a rotating bobbin 17 and moves progressively forward until a predetermined size of bobbin is formed. This is accomplished by a thread guide carrier 18 which is slidably on guide rods and secured by its clamping portion 14a to a chain 16 which is intermittently moved from left to right as viewed in Fig. 1, by a ratchet and pawl assembly 18. When the main winding has been accomplished, a lug 15 on the thread guide carrier hits an adjustable stop 19 fixed to a rod 21. The latter member is slidably held under tension in a bearing 23 and extends rearwardly to a point where it is attached to an arm 25, in turn controlling the start of rotative movement of a doffing shaft 12, the mechanism within the casing for that purpose being similar to that described in U. S. Patent 2,268,308.

As the lug 15 hits the stop 19 and moves the rod 21 a predetermined distance, the doffing shaft starts to rotate and makes one complete turn at a rather slow speed, that being the only turn or revolution it makes during a single cycle. During this single rotation of the doffing shaft, the bobbin makes its last few revolutions. This interval is utilized, conventionally, for back-wind, or for winding down a so-called "tail" over the package, where such an operation is desired. The bobbin is then usually transferred to a hopper and a new bobbin is inserted and threaded to begin another winding operation, all as described in that patent. A carriage retraction cam 22 on doffing shaft 12, during the rotation of the latter member, actuates an arm 20, which causes the pawls for the ratchet wheel at 18 to be withdrawn, whereupon the thread guide carrier is retracted by weights or springs, as the case may be.

In accordance with the present invention, the above described conventional movements are left undisturbed. However, movement of the doffing shaft is utilized, and particularly that interval during its rotation when back-wind is conventionally provided for, and while the spindle is making its last few revolutions, to effect the building and treatment of the finding bunch.

On the doffing shaft, I provide a cam member 24 (Figs. 1, 7 and 9). This cam is rotatively adjustably mounted on the doffing shaft adjacent to the cam 22 in the manner shown in the drawings.

A screw 22a (Fig. 7), passing through an arcuate slot 22b in the carriage retraction cam 22 and through a similar slot in flange 22c fixed to the doffing shaft, is threaded into inside tip bunch building cam 24, Fig. 7. It will be seen that this screw affords a simultaneous adjustment of the angular positions of both cams 22 and 24 on the doffing shaft. The doffing shaft with attached flange 22c, cam 22, and cam 24, rotate as a unit in whatever angular relation they may have been adjusted together by means of this screw. The doffing shaft rotates in an anti-clockwise direction, as viewed in Fig. 1. It will be observed therefore that a clockwise adjustment of cam 22 relative to the doffing shaft, effects a later retraction of carriage 14-A. Adjustment of cam 24 varies the time at which the finding bunch is started while the position of cam 22 determines the size of the bunch by advancing or retarding as desired, the return of the carriage.

Directly above the cam 24 is a lever 28 mounted on a pivot 29. Projecting downwardly from the lever is a tip 26 adapted to be engaged

by the cam 24 in the position of the latter member illustrated in Fig. 1. Movement of the cam releases the lever, allowing it to rotate in a counterclockwise direction as viewed in the figure noted, such rotation being determined by the influence of spring 34.

At its upper extremity, the lever 28 is formed with a slot 31, through which is received a rod 32 which extends along the entire side of the winder. The left-hand end of rod 32, as viewed in Fig. 1, is passed through a bracket 41 and carries a compressed spring member 34 which normally tends to pull the rod member toward the back of the winding head or in a direction from right to left as viewed in Fig. 1.

Numeral 40 denotes a spacing collar secured on the rod at a point adjacent to the top of the slotted pawl. At the opposite side of the slotted pawl is a stop member 30, adjustably fixed to the rod. The rod carries at its intermediate portions a bracket 42 and has its end supported in a bearing 43 at the opposite end of the winder. An actuating dog or stop member 36 is fixed on the rod in spaced relation to the bearing 43. The arm of the thread guide 14 is formed with a tail piece 38 which projects downwardly into the path of movement of the dog 36 when retracted by the rod 32.

At the extreme right-hand end of Fig. 1 are shown two split collar sections 46 and 48 which form a clamp and are secured on a relatively fixed cylindrical member of the winder by screws or other clamping means. The top collar section 48 has pivotally mounted thereon on a shaft which extends upwardly therefrom a block 50 which is secured by means of a sleeve portion 52. Extending through the top collar section is a thread deflecting stop 44, whose inner extremity is bent into the form of a right angle positioned at a point above the end of the spindle. A second stop member 54 mounted through the oscillatable block 50 also projects in the direction of the bobbin and slightly to one side thereof in the path of movement of the arm carrying the thread guide 14. The block 50 is formed with an arm 56, which carries a container 58 in which is received an adhesive material. At the base of the container is connected a sleeve-type ball applicator, better shown in Figs. 3, 4 and 6. This applicator includes a cylindrical member, a resiliently held ball 62, and a back plate formed with an aperture 64. The bearing block 50 is normally held in the position shown in Fig. 3 by means of a spring supported by stop 66. A second stop 68 maintains the block in the position noted in Fig. 3 until disturbed from position shown, by virtue of arm (carrying thread guide 14) striking against arm 54.

In operation, as soon as the main winding of the package has been completed, the lug 15 on the thread guide carrier hits the adjustable stop 19, causing the doffing shaft to start its rotation through one revolution and then coming to rest. During that revolution the doffing shaft causes a number of movements to take place in substantially the following order: Rotation of the bunch builder cam 24 releases the engaging lever 28, in turn permitting the spring 34 to retract the long rod 32 to a position limited by a spacing collar 40 striking bracket 41. The dog 36 near the forward end of the rod 32, in moving rearwardly picks up the tail piece 38 on the thread guide holder, thereby swinging the thread guide arm to a position further toward the tip 26 of the bobbin so that the thread may be wound

at a point adjacent the end of the bobbin and in spaced relation to the main package of filling. In this position of the guide, the thread 10 is pressed against the extremity of the thread-deflecting stop 44, which causes a number of turns to be wound at one localized area on the bobbin, thus building the finding bunch 72, Figs. 2 and 3. Spindle rotation is then stopped. The thread carrier is next retracted, the spindle head is retracted from driving contact with the bobbin, and the bobbin is dropped into a hopper in the usual way where it is temporarily held until thread between the filled and a newly entering bobbin is severed. The bobbin is then allowed to fall into a container in the usual manner. The doffing shaft 12 continues its rotation to a point near the end of its revolution with the attached bunch builder cam 24 then picking up the tip 26 of the lever 28 and restoring the tip bunch building control mechanism to a starting position. From this point on, a new bobbin is inserted and threaded, a reserve bunch is built, and the main winding is resumed to repeat the cycle of operation. The cam 22 determines the proper point of retraction of the thread guide carrier by tripping the return mechanism in a conventional manner. Of course, that is done right after the tip bunch has been completed.

Operation of the adhesive applying mechanism occurs as hereinafter described during winding the tip bunch and is begun by moving the arm of the thread guide 14 into the extreme position above described. As the arm swings to the right, due to the action of the retracted rod 32 against the tail piece 38, it comes into contact with a hook member 54 and rotates the whole applicator unit, including the block 50, the container 58, and the applicator 60, until the stop screw 66 hits against the upper collar section 48, as may be more clearly observed in Fig. 5.

Meanwhile the bunch 72 is being built and during its winding, the ball 62 is brought into contact with the bunch with a positive pressure which depresses the ball against the action of its retaining spring, thus allowing adhesive material to escape by the ball on to the bunch. The action of the sealer is very fast, with the ball contacting the filling for a very short period during which most of the turns are stuck together, although the adhesive material does not come into contact with the underlying surface of the bobbin. When the thread guide is retracted, the block 50 springs back to a starting position limited by a set screw 68 striking against the upper portion of the collar section 48.

It should be observed that the orifice 64 in the applicator tube permits adhesive to fill the space around the ball and applicator tip in a time interval sufficient for supplying each single tip bunch but functions to prohibit a sudden return of fluid to the container and prevents application of an excess of adhesive. The adhesive is preferably one which sets relatively quickly and which produces a rather tight bond or adhesion between adjacent turns of thread. An adhesive employing a starch or glue base, containing an agent for inducing quick drying, may be used.

By reducing the adhesive property of the cementing fluid, and by accentuating the quick-drying property of the fluid so that it is better adapted to the specific time interval available during the building of the tip or finding bunch, very satisfactory bonding results may be obtained. At the same time, by using only very small amounts of the adhesive as limited by the

10 ball and sleeve type applicator described, a controlled sealing operation is carried out. Release of adhesive is so timed by setting the member 54 that two or three, or possibly more layers of bunch filling are formed before the bunch builds up to a size sufficient to depress the ball and allow adhesive to escape on to the bunch. Due to this timing, the adhesive is prevented from directly coming into contact with the bobbin surface.

15 It is pointed out that due to the character of the adhesive and the manner in which it is applied, it becomes possible to carry out a carefully controlled degree of sealing. This avoids sticking the thread upon the bobbin tip and yet the adhesive is so applied that practically each involved turn in the bunch 72 is relatively firmly attached to adjacent turns, thus requiring a reasonably strong pull or vigorous handling to separate the turns of the thread and in this way avoiding undesirable raveling or unwinding of the filling bunch. Since the bunch as a whole may be readily separated from the spindle, it serves as a convenient body which can be grasped and held by hand or by automatic mechanism such as grippers, either to clear the filling in preparation for hand-tying, or to hold the filling during automatic installation and manipulation in a battery.

20 30 In the Whitin-Schweitzer winder shown in the drawings, the thread 9 passes from a supply, under tension, through thread guide 10 supported on a control arm 10a, and thence on through oscillating thread guide 14 and to the package. 35 Any release of tension in the thread allows arm 10a to be drawn toward the rear (under influence of a spring). This stops the machine. The stopping motion acts whenever the supply becomes exhausted or the thread breaks for any reason. 40 This arrangement is subject to the difficulty of undesired stopping. As the thread slacks up when the carriage retracts, carrying the thread from the front end of the bobbin toward the rear, the bobbin falls into a hopper, and during this falling, further slack is given the thread. 45 The resulting decrease in tension on the thread allows the control arm 10a to stop the machine.

50 A further important aspect of the invention includes means for overcoming this unintended stopping. The addition of the long rod 32 furnishes a means of holding arm 10a in an inoperative range during the doffing cycle when the thread tends to slacken; but allows arm 10a to remain operative at all other times.

55 55 When rod 32 moves rearwardly an abutment 42, which is adjustably fixed on rod 32 by clamping dog 42a, strikes tab 42b on a pivoted arm 42c which is held under tension in the position shown in Fig. 1. The arm 42c is thus rotated and its 60 end 42d is brought into a position such that it holds arm 10a from operating through its normal range or swinging sufficiently to stop the machine. As the position noted need only be assumed for a short interval during the doffing cycle, the control arm 10a functions in its usual manner at all other times.

65 70 It will be evident from the foregoing description that the structure of the invention and the method of operation noted afford several advantages. The difficulty and loss of time resulting from attempting to clear the back wind of a bobbin prior to being inserted in a battery is greatly reduced since the bunch presents a convenient body which may be gripped by an operator and easily pulled off over the end of the

spindle. The use of a clearing bunch at the point noted is further advantageous in making possible automatic removal of the bunch and automatic tying of the end of the thread in a loom battery. The particular arrangement of parts is so designed that no interference with the normal operation of the machine is caused.

In the specification and claims the terms yarn and thread have been used more or less interchangeably, and the invention is by no means limited to winding a single spun strand or to a thread combined from several strands, but is equally applicable to winding a tip bunch after and spaced from the main yarn package during the formation of such a package from any yarn, filament, thread or combination thereof.

It is intended that the method may be modified in various respects, and the particular bunch building mechanism may be varied in accordance with the scope of the invention as defined by the appended claims.

I claim:

1. A filling bobbin winder comprising means for supporting and rotating a bobbin, an oscillating thread guide member for building a main package on the bobbin, doffing mechanism operative upon completion of said main package on the bobbin, means actuated by said doffing mechanism for advancing the oscillating thread guide into a position directly above the outer end of the bobbin, and thread-deflecting means separate from the oscillating thread guide for limiting the traverse of the thread as it is applied by the oscillating thread guide in its advanced position to form a tip bunch.

2. A filling bobbin winder comprising means for supporting and rotating a bobbin, an oscillating thread guide member for building a main package on a bobbin, doffing mechanism operative upon completion of the main package on the bobbin, a retracting element slidably secured adjacent to the oscillating thread guide member, cam means driven by said doffing mechanism, said cam means being operatively connected to the retracting element to provide movement thereof, stop means on said retracting element adapted to engage against the said thread guide member and move the latter member into an advanced position above the tip end of the bobbin, thread-deflecting means arranged in the path of movement of thread passing from the thread guide in its advanced position, thereby to cause the thread guide to lay a finding bunch of filling on the bobbin in spaced relation to the said main package.

3. In a filling bobbin winder, the combination of means for supporting and rotating a bobbin, an oscillating thread guide member, doffing mechanism, a rod member secured at one side of the winder, means forming a part of the doffing mechanism for retracting said rod during the doffing cycle, a stop member fixed on the rod, a tailpiece extending from the oscillating thread guide into the path of movement of the stop member on the rod during the doffing cycle, said tailpiece, when the rod is retracted, being adapted to move the thread guide into an advanced position above the bobbin tip and thread-deflecting means for limiting the traverse of the thread as it passes from the thread guide in its advanced position.

4. In a filling bobbin winder, the combination of means for supporting and rotating a bobbin, an oscillating thread guide member, doffing mechanism, a retracting rod member arranged

75 to build a finding bunch of filling in spaced relation to a main package on the bobbin including a traversing yarn guide, means for applying adhesive material to the bunch as it is being built

at one side of the winder, and bearing members at opposite ends of the winder for receiving the extremities of said rod a pivoted member engaging said rod, a cam responsive to movement of the doffing mechanism, operatively connected to the said pivoted member, thereby to retract the rod member when the doffing mechanism is actuated, a stop member fixed on the said retracting rod, said oscillating thread guide member having an extension projecting angularly downward into the path of movement of the stop member, said extension being effective upon engagement by the stop member to move the thread guide into an advanced position above the bobbin extremity, and means for limiting the traverse of the thread passing from the thread guide in its advanced position.

5. In a filling bobbin winder, means for supporting and rotating a bobbin, an oscillating thread guide member for winding a main package on the bobbin, doffing mechanism including a doffing shaft extending out from one side of the winder, a cam member fixed on the shaft for causing retraction of the thread guide member, means for advancing the thread guide and building a finding bunch of filling on the bobbin in spaced relation to the said main package, said means including a builder cam secured on the doffing shaft adjacent the said retracting cam, said builder cam being so positioned on the shaft in relation to the retracting cam as to provide an interval between the bunch building or thread guide advancing movement and retraction of the thread guide member.

6. In a filling bobbin winder, means for supporting and rotating a bobbin, an oscillating thread guide member for winding a main package on the bobbin, doffing mechanism including a doffing shaft extending out from one side of the winder, a cam member fixed on the shaft for causing retraction of the thread guide, means for advancing the thread guide and building a finding bunch of filling on the bobbin in spaced relation to the said main package, said means including a builder cam secured on the doffing shaft adjacent the said retracting cam, said builder cam being adjustable relative to the retracting cam in order to vary the number of turns on the said spaced-apart finding bunch of filling.

7. In a filling bobbin winder, means for supporting and rotating a bobbin, an oscillating thread guide member for winding a main package on the bobbin, doffing mechanism including a doffing shaft extending out from one side of the winder, a cam member fixed on the shaft for causing retraction of the thread guide, means for advancing the thread guide and applying a finding bunch of filling on the bobbin in spaced relation to the said main package, said means including a builder cam secured on the doffing shaft adjacent the said retracting cam, said builder cam being formed with a slot, a fastening member extending through the slot and engaging with the retracting cam, the respective positions of the builder cam and retracting cam on the doffing shaft being adjustable so that said doffing shaft at the beginning of its rotation actuates the builder cam and at the latter part of its rotation actuates the retracting cam.

8. In a filling bobbin winder, means for building a finding bunch of filling in spaced relation to a main package on the bobbin including a traversing yarn guide, means for applying adhesive material to the bunch as it is being built

said adhesive applying means including a supporting member, a pivoted arm mounted on the supporting member, an adhesive applicator received at the end of the pivoted arm, said applicator including a tubular member and valve means for permitting release of adhesive material therefrom, and a member projecting from said supporting member and into the path of said traversing yarn guide to be moved thereby when the yarn guide is moved to finding bunch building position, until the applicator is brought into engagement with the yarn in said bunch, whereby said pivoted arm is controlled by movement of the finding bunch building means for applying the adhesive.

9. In a filling bobbin winder, means for supporting and rotating a bobbin, an oscillating thread guide member for winding a filling thread to form a main yarn package and a tip filling bunch on said bobbin and means for moving said oscillating thread guide member into an advanced position overlying the end of the bobbin, a thread-deflecting element arranged to lie in the path of movement of the thread as it passes from the oscillating thread guide member in its advanced position, a supporting member within which said thread-deflecting element is secured, a block mounted to pivot on the supporting member, a projecting stop member fixed in the pivoted block and lying in a position in which it is engaged by the said thread guide when the latter is moved into its advanced position, an adhesive applicator element carried by the said pivoted block, said applicator being adapted to be moved as the thread guide member contacts the said projecting stop member, into a position to contact and to apply adhesive to the said tip filling bunch as it is being wound.

10. In a filling winder, means for supporting and rotating a bobbin, an oscillating thread guide member for winding a main package and a tip finding bunch on the bobbin, doffing means including a doffing control shaft, cam means mounted on said doffing shaft, a lever resiliently mounted and having a toe in contact with the cam, a rod member secured to the lever, a stop member fixed adjacent the opposite end of the rod, said thread guide having a projecting end disposed so that during its progressive movement it is engaged by the said stop member, a thread-deflecting stop mounted in the path of movement of the thread passing from the thread guide when it assumes a position to wind the tip bunch, and a sealing mechanism cooperating with the movement of the arm of the thread guide member as it moves into its tip bunch winding position, said sealing mechanism being adapted to apply a controlled amount of adhesive material to turns of filling supplied from the thread guide during winding the tip bunch.

11. In a filling bobbin winder, means for supporting and rotating a bobbin, an oscillating thread guide member for winding a main package and a tip finding bunch on the bobbin, a movable arm through which the thread is passed, said arm being responsive to drop in thread tension for initiating the movement of mechanism to interrupt the operation of the winder, doffing mechanism including a doffing shaft extending out from one side of the winder, means for advancing the thread guide after completion of the main package to wind the finding bunch of filling on the bobbin in spaced relation to the said main package, said means including a tip bunch controlling builder cam secured on the doffing shaft,

a pivoted stop member movable to a position in the pathway of said movable arm and means responsive to movement of the tip bunch controlling builder cam and interconnected to said pivoted stop member for preventing the arm from moving sufficiently to initiate stopping of the machine during winding the tip finding bunch.

12. In a machine for winding a yarn package, means for supporting and rotating a core on which said package is to be formed, an oscillating guide member for traversing the yarn along the core to build a main yarn package thereon, means for terminating the winding of the main package and for rapidly moving the oscillating guide to a position for winding its yarn at a point closer to the tip end of the core and spaced from the adjacent end of the main package, and a stop member functioning between the oscillating guide member and core for engaging the yarn to confine its traverse to a distance substantially less than that imparted by the guide thereby to wind a relatively small, tip finding bunch.

13. In a machine for winding a yarn package, means for supporting and rotating a core on which said package is to be formed, an oscillating guide member for traversing the yarn along the core to build a main yarn package thereon, means for terminating the winding of the main yarn package including a cam group rotatable at a predetermined point in the winding cycle, and means responsive to movement of one of the cams which comprise said group for rapidly moving the oscillating guide to a position for winding its yarn at a point closer to the tip end of the core and spaced from the adjacent end of the main package, a yarn stop member for confining the traverse of the yarn within a distance less than the traverse imparted by the guide to wind a relatively small tip finding bunch, and means responsive to another of said cams which comprise said group for terminating the winding of the tip bunch by returning the oscillating guide to its original position at the base of the package.

14. In a machine for winding a yarn package, means for supporting and rotating a bobbin on which said package is to be formed, an oscillating yarn guide for traversing the yarn and means for progressively moving said guide along the bobbin to build a weft wound, main yarn package thereon, means for terminating the winding of the package and for controlling the doffing thereof which includes a doffing shaft and cam group carried thereby, said shaft and cam group being rotatable for a single revolution at a predetermined point in the winding cycle, and means tripped by one of the cams in said group and engageable with a portion of said oscillating guide means for rapidly moving it to a position for winding its yarn at a point closer to the tip end of the bobbin and spaced from the adjacent end of the main package, a yarn stop member for confining the traverse of the yarn within a distance less than the traverse imparted by the guide to wind a relatively small tip finding bunch, and means responsive to another of the cams of said group for terminating the winding of the tip bunch by returning the oscillating guide to its original position at the base of the package.

15. In a machine for winding a yarn package, means for supporting and rotating a core on which said package is to be formed, an oscillating guide member for traversing the yarn along the core to build a main yarn package thereon, means for terminating the winding of the main package and for rapidly moving the oscillating guide to a

position for winding its yarn at a point closer to the tip end of the core and spaced from the adjacent end of the main package, and means comprising a stationary yarn engaging stop member for substantially decreasing the effective length of traverse of the yarn as controlled by the oscillating guide member thereby to wind a relatively small tip finding bunch.

16. A method of building a yarn package and tip finding bunch on a core which comprises the steps of forming a main yarn package on the core and terminating said main yarn package at a substantial distance from the tip end of the core, continuing the winding of the yarn at a point more closely adjacent the tip end of the core and spaced from the adjacent end of the main yarn package to form a tip bunch, and applying adhesive to the convolutions of yarn in the tip bunch after the start of winding thereof to adhere the said convolutions together without adhering the bunch itself to the surface of the core.

17. A method of building a yarn package and tip finding bunch on a core which comprises the steps of forming a main yarn package on the core and terminating said main yarn package at a substantial distance from the tip end of the core, continuing the winding of the yarn at a point more closely adjacent the tip end of the core and spaced from the adjacent end of the main yarn package to form a tip bunch, and applying adhesive to the convolutions of yarn in the tip bunch after winding at least one layer of yarn on the core thereby to adhere the convolutions together without adhering the bunch itself to the surface of the core.

18. A method of winding a yarn package and tip finding bunch on a bobbin which comprises the steps of forming a main yarn package by traversing the yarn along the bobbin and building the package to a point at which it is terminated at a substantial distance from the tip end of the core, continuing the winding of the yarn at a point more closely adjacent the tip end of the bobbin and spaced from the adjacent end of the main yarn package to form a tip bunch, and applying adhesive to the convolutions of yarn in the tip bunch after winding at least one complete layer thereof on the bobbin to adhere the said convolutions together without adhering the bunch itself to the surface of the core.

19. A method of winding a weft yarn package and a tip finding bunch on a bobbin which comprises the steps of forming a main yarn package on the bobbin by traversing the yarn and building the package to a point at which it is terminated at a substantial distance from the tip end of the bobbin, continuing the winding of the yarn at a point more closely adjacent the tip end of the bobbin and spaced from the adjacent end of the main yarn package to form a tip bunch, and, after winding at least one complete layer of yarn at the tip bunch, applying an adhesive to the convolutions of yarn thereafter wound in the tip bunch thereby to adhere the bunch together without adhering it to the surface of the bobbin.

20. A winding machine including means for rotating a winding bobbin, a thread guide cooperating with the winding bobbin to distribute the thread into a main wound body thereon, means for shifting the thread guide from a position adjacent to the tip portion of the bobbin to a position adjacent to the position to be occupied by the base of the next bobbin to be wound, a guide member positioned to intercept the thread adjacent to the region between the main wound body and the tip of the bobbin, and means for rotating the bobbin to wind end-finding coils between the main wound body and the tip of the bobbin while the thread is guided onto the bobbin by said guide member.

EDWARD J. BERRY.
